United States Patent Office

Des. 210,104
Patented Feb. 6, 1968

210,104

MACHINE FOR MOUNTING FILM ON CARDS

Robert G. Plantholt, Rochester, Mich., assignor to The Scionics Corporation, Northridge, Calif., a corporation of California

Filed Aug. 2, 1966, Ser. No. 3,310

Term of patent 14 years

(Cl. D61—1)

FIG. 3.

FIG. 4.

FIG. 1 is a perspective view of a machine for mounting film on cards showing my new design.

FIG. 2 is a side view of the same.

FIG. 3 is a top plan view of the same.

FIG. 4 is a rear elevational view of the same.

I claim:

The ornamental design for a machine for mounting film on cards, as shown.
